UNITED STATES PATENT OFFICE

EDGAR W. MYERS, OF LOS ANGELES, CALIFORNIA

APPARATUS FOR AMALGAMATING METALS

Application filed January 15, 1926. Serial No. 81,547.

My invention relates to the extraction of precious metals from ores by amalgamation, my object, generally stated, being to obtain a larger percentage of the metals and to save time and cost in the treatment, and thus do the work economically.

Briefly described, by my invention the metal-containing ores, in finely ground condition, are subdivided into a number of streams and are fed continuously and the several streams are subjected to a steam scouring process which cleans and separates and tends to classify the ore as it passes through the apparatus, preparatory to delivery to screening means for separating the finer parts for delivery to a mercury pot, the matter not entering the latter being passed over screens and disposed of. The result is that the ore is most advantageously handled for thorough and rapid treatment for the recovery of the precious metals therein.

My invention consists in whatever is described by or is included in the terms or scope of the appended claims.

In the accompanying drawings:

Fig. 1 is a side elevation partly in vertical section of an apparatus embodying my invention;

Fig. 2 is a horizontal section on line 2—2 of Fig. 1;

Fig. 3 is a horizontal section on line 3—3 of Fig. 1;

Fig. 4 is a section on line 4—4 of Fig. 1;

Fig. 5 is a section on line 5—5 of Fig. 1;

Fig. 6 is a section on line 6—6 of Fig. 1;

Fig. 7 is a section on line 7—7 of Fig. 1.

Referring in detail to the drawings, at the top of the apparatus is a receiving hopper, 10, into which the ground ore is discharged, and from which it descends into a chute, 11, by which it is fed to a cylindrical chamber, 12, in the lower part of which are paddles, or wings, 14, carried by a vertical shaft, 13, which is revolved to rotate the paddles, 14. The shaft, 13, has at its upper end, a turbine-form drive wheel, 16, adapted to be driven by a steam jet that by a supply pipe, 17, enters the wheel casing, 18, formed in the upper part of said chamber, 12. Said shaft,

13, may be provided, if desired, at its end with a balance wheel, 19.

By the paddles, the ore is stirred and pushed outward into a plurality of outwardly and downwardly inclined passages, 15, by which the body of ore is subdivided into a number of small streams, and thereby fitted for the highly efficient steam and other treatment that follows.

Encircling the said passageways or conduits, 15, is an annular steam box, 20, that receives steam from a pipe, 21, and from this annular steam box are vertical branches, 22, of inverted L-form, each with a vertical passage, 23, and a horizontal passage, 24. From the latter a steam jet or nozzle, 26, discharges steam downward into the top of each of the conduits, 15, clearly indicated at the left of Fig. 1. A screw plug, 27, closes a hole that gives access to the nozzle, 26, and a screw plug, 28, closes a hole that gives access to passage, 23. If it is desired to close communication between passages 23 and 24, for any purpose, as for example, to cut a branch out of action, the plug, 28, being first removed, a plug can be screwed into the threaded hole, 25, provided in a partition between the two passages, 23 and 24.

It will be seen that the ore moves down into the cylindrical chamber, 12, where it is stirred and pushed out into the conduits, 15, in several small streams, and thus subdivided, each stream is acted on by a strong jet of steam that blows it downward and breaks it up and scours it.

Each conduit, 15, is prolonged downward by an extension, 15a, that at its lower end rests on and is secured to a casting, 30, that contains an annular chamber, 31, that by a central, circular partition, 30a, and the radial partitions, 30b, (see Fig. 5), is subdivided into as many compartments as there are conduits, 15, and into which the latter respectively discharge, and each being of greater volume than the outlet extension, 15a, the steam expands and with it the ore particles enveloped thereby, and thus, such particles are loosened up and separated from one another, and thus prepared for the next step in the process.

The casting, 30, rests upon a ring, 35, supported upon the upper end of a downwardly enlarging, tapering shell, 36, having at one side near the bottom an outlet, 37, from which leads a short spout, 38. The ring, 35, has formed as a part thereof an inwardly and downwardly extending casting, 39, in which is formed adjacent the ring an annular channel, 40, and at the lower end of which casting is a central annular flange, 41. A mercury pot, 42, fits within the chamber enclosed by said casting, 39, and has a central cylindrical wall, 43, between the top of which and the outer rim of the pot, extends a conical screen, 44, that has an open center 44a in register with the space surrounded by the wall, 43. The bottom of the annular channel, 40, as shown in Fig. 1, inclines downwardly from one side to the opposite side, and at its lowest point has an outlet opening, 40a, so that any overflow from the mercury pot, or the screen, 44, or any discharge thereinto from above, will flow to and out through the opening, 40a. Matter passing through the screen, 44, will remain in the mercury pot, 42, which can be lifted out bodily, after lifting the upper part of the machine from the annular ring, 35, for which purpose a vertical bolt, 33, is attached to the center of the casting top, 30c, that above the fly wheel, 19, has a hook, 34, for attaching a derrick or other lifting means.

The outlet, 40a, discharges into a trap or pocket, 46, below it, and from such pocket, 35, a trough, 45, inclines downwardly and passes at its lower end through the opening, 37, and the spout, 38. The pocket, 46, has a rear wall, 47, which extends alongside of the outlet, 40a, and above the bottom thereof.

At a point about midway between its upper and lower ends the trough, 45, has a discharge opening, 50, in its bottom, and above such opening there is a screen, 48, to prevent the entrance into and passage from the discharge opening, 50, of matter too large, the matter passing over the screen including what flows from the trough, 46, and which passes through the central opening in the screen and that enclosed by the wall, 43, in the mercury pot. Thus, only material of the desired fineness will pass through the screen, 48, and be discharged through the trough outlet, 50, the larger pieces or particles being discharged from the bottom of the trough, 45. Near the lower end of the screen, 48, there is a transverse catch-forming depression or channel, 49.

The discharge from the trough outlet, 50, falls into a chamber that is enclosed by a substantial cylindrical base, 51, upon the top of which is mounted the casting, 36, the top of the base being open, and such base having a bottom, 54, which inclines from the side near the discharge end of the trough, 45, to the opposite side of the base, and just

above the lowest portion of said bottom, 54, an outlet pipe, 57, leads, which by oppositely extending branches, 58, passes concentrates from the base, 51, into two vertical tanks, 59 and 60, from which the concentrates may be delivered to a concentrating table. Each tank has an outlet, 63, at its bottom for the removal of its contents. Within the tanks there may be either super-atmospheric pressure or sub-atmospheric pressure, whichever may be desired. Super-atmospheric pressure may be secured by the steam and heat within the tanks, all outlets being closed in an air-tight manner, including openings at the top which are closed by screw plugs, 62. If a partial vacuum is desired, that may be secured by connecting an air pump with a pipe, 61, that communicates with the interior of the tank.

At the top of the base, 51, there are numerous holes, 53, opening through the side walls for the discharge of water in the base when it reaches the level of those holes, and water passing through such holes is received by a downwardly inclined trough or channel, 55, which has at its lowest point a discharge outlet, 56. The top of the base, 51, opposite the holes, 53, is encircled by a ring, 52, having a vertical partition which is opposite the holes against which water flowing through the holes will strike and be directed into the trough, 55, and a horizontal portion is situated between the bottom of the casting, 36, and the top of the base, 51. Just above the lowest point of the inclined bottom, 54, is a hole, closed by a plug, 64, for the discharge or removal of sediment or settling and any mercury that may settle in the chamber within the base, 51.

To relieve or cushion pressure created or existing within the casting, 31, there are several pipes, 65, which extend upward from the top thereof, and which conveniently may have an L-shape, and opening through the casting, 31, into the chamber within the same are several nipples, 32, closed by removable caps.

I have referred to the use of steam for revolving the turbine, 16. Of course, water may be used for that purpose. The steam or other fluid so used is exhausted through outlet openings, 66, which discharge into the feed chute, 11, and serves to disintegrate or break up the ore passing through the chute, and by pressure thereon supplements gravity to force the ore through the chute and into the chamber, 12.

Describing in its entirety the process or operation in connection with the embodiment of my invention illustrated in the drawings, the pulp or ground ore, passing from the hopper, 10, into the chute, 11, is first acted upon by the exhaust steam or other pressure fluid for rotating the paddles, 14, being thereby disintegrated to some extent and cleansed

and then being acted upon by the paddles, 14, which stir up the mass, and force it into conduits, 15, which subdivide it into numerous small streams and the streams are next acted upon by the steam issuing from the nozzles, 26, which breaks up the ore and scours it and forces it downward through the conduits, 15. From the lower contracted portions, 15a, of such conduits, the subdivided streams enter the chambers within the casting, 31, in which an expansion of the steam takes place and the separation of particles or pieces of ore, this action being promoted by the increase of pressure which takes place due to the contraction of the lower portions, 15a, of the conduits. The larger portions of the streams or subdivisions then together pass to the screen, 44, above the mercury pot, 42, and the particles small enough to pass through the stream fall into the mercury pot for amalgamation. The mercury is kept in a heated condition to promote the amalgamating action by hot water or condensed steam in the space surrounding the mercury pot within the casting, 39, and, of course, the steam treatment to which the pulp was previously subjected results in heating thereof. Only portions of the ore which fall into the channel, 40, and which pass through the central opening through the mercury pot and the casting, 39, find their way to the trough, 45, either directly or indirectly from the pocket, 46, passing over the screen, 48, in the trough, 45, the finer particles are delivered to the chamber within the base, 51, which is filled with hot water and the parts too large to pass through the screen, 48, are discharged from the lower end of the trough, 45. The chamber within the base, 51, is filled with hot water preliminary to starting the machine and water is taken from the base as by means of a pipe, 510, and delivered to the top of the machine and circulated therethrough with the steam, so that there is a continuous flow of pulp accompanied with steam and hot water from the top to the bottom of the machine, the result being that the ore is heated, the particles separated and scoured and placed in the best condition for amalgamation, which makes for an increase in percentage of recovery of the metals and with a minimum of handling and expenditure of power.

The pressure of the steam acting upon the pulp in the several conduits varies according to the requirements of the pulp being treated and a steam gauge, 76 (see Fig. 1), as shown in the drawings, is applied to each conduit.

It is to be understood, as I have already indicated, that my invention is not restricted to the particular construction of apparatus illustrated in the drawings. For example, the number of passages, 15, by which the subdivision of the pulp or ground ore is pre-

liminarily affected, may be greater than is shown in the drawings, and other changes may be made without departure from my invention, it being my intention not to restrict myself beyond the requirements of the legal meaning of the following claims.

What I claim is:

1. Amalgamating apparatus comprising an initial pulp receiving chamber, a plurality of pulp passages leading from such chamber, means for subjecting pulp while in such passages to a heated fluid, and a mercury container to which all such passages lead, said passages being separate up to the point where they communicate with said container, a water chamber below such mercury container, means preventing passage of part of the ore into the mercury container, and means for delivering to such chamber portions of the ore which do not enter the mercury container.

2. Amalgamating apparatus comprising an initial pulp receiving chamber, a plurality of pulp passages leading from such chamber, means for subjecting pulp while in such passages to a heated fluid, and a mercury container to which all such passages lead, said passages being separate up to the point where they communicate with said container, a water chamber below such mercury container and means for delivering to such chamber portions of the ore, said means comprising screening means which remove portions of the ore not desirable to deliver to said chamber.

3. Amalgamating apparatus comprising a mercury pot having a through central opening walled off from the mercury containing portion of the pot, a plurality of separate chambers immediately above said pot and outside said opening means for delivering separated streams of pulp and steam to such chambers, and a screen over such pot having a central opening registering with the mercury pot opening and sides inclined toward said opening to convey unscreened particles to the opening registering with the mercury pot opening.

4. Amalgamating apparatus comprising a mercury pot having a screen at the top, a support for said pot having an annular channel around the rim thereof, not covered by the screen and with an inclined bottom, said bottom at a low point having an outlet and a settling pocket receiving material from said outlet.

5. Amalgamating apparatus comprising a mercury pot having a screen at the top, a support for said pot with a central opening through the screen and pot having an annular channel around the rim thereof, not covered by the screen and with an inclined bottom, said bottom at a low point having an outlet and a settling pocket receiving material from said outlet, and a downwardly inclined trough leading from said settling

pocket, across and beneath the said central opening and having a screened outlet intermediate its ends.

6. Amalgamating apparatus comprising an inlet feed chute, a chamber to which said chute delivers pulp, rotary pulp engaging members in such chamber, a fluid actuated impeller for rotating said members, and means for passing the exhaust from the impeller into said chute in advance of communication between the chute and said chamber.

7. Amalgamating apparatus comprising a pulp receiving chamber, a plurality of passages communicating with said chamber, revolving means in said chamber for stirring said pulp and forcing it out into said passages, a steam discharge nozzle in each passage for forcing steam into said pulp to heat, scour and break it up, a mercury pot, means for heating the same, a screen over said mercury pot for screening metal-containing pulp, means for catching the coarser matter from said screen, an over-flow trough having an opening under said screen, a base having a receiving chamber for said screened matter, with an inclined bottom to receive and settle the heavier matter falling into the base, and means for collecting concentrates connected with said base member.

8. Amalgamating apparatus comprising a mercury container, means for preparing the pulp situated directly above such container, means for passing the prepared pulp downward from the preparing means to the container, a shell surrounding the mercury container in the upper part of which the mercury container is located, a base upon which said shell rests, said base having a water-receiving chamber, a trough situated within said shell and extending to a point outside the same and having an outlet into the top of said water-receiving chamber, said trough being situated to receive discharge from the mercury container and matter diverted therefrom, and a tank adjacent said base chamber and in communication with such chamber.

In testimony whereof I hereunto affix my signature.

EDGAR W. MYERS.
